UNITED STATES PATENT OFFICE.

CHARLES WRIGHT, OF CATLETTSBURG, KENTUCKY.

IMPROVEMENT IN BOILER-FEEDERS.

Specification forming part of Letters Patent No. 147,886, dated February 24, 1874; application filed December 20, 1873.

To all whom it may concern:

Be it known that I, CHARLES WRIGHT, of Catlettsburg, in the county of Boyd and State of Kentucky, have invented a new and useful Improvement in Boiler-Feeder, of which the following is a specification:

Figure 1 is a vertical section of my improved boiler-feeder, taken through the line $x\ x$, Fig. 2. Fig. 2 is a horizontal section of the same, taken through the line $y\ y$, Fig. 1.

Similar letters of reference indicate corresponding parts.

My invention has for its object to furnish an improved device for feeding water to a steam-boiler, which shall be simple in construction, convenient in use, easily operated, and reliable in operation. The invention consists in the case, the bottom, provided with the four passages and the two stops, the valve, provided with the two passages and the stop, and the interior pipe, constructed and arranged to operate, in connection with each other, a steam-boiler, and a supply-cistern, as hereinafter fully described.

A represents a case or chamber, the upper end of which is made close, and which has a flange formed around its lower end, by means of which it is bolted to the bottom B. C is a valve, which has its seat upon the middle part of the inner surface of the bottom B, and is attached to the stem D, which passes out through the center of the bottom B, and has a crank arm or handle, E, attached to its outer end. The inner end of the valve-stem D rests against the end of a screw, F, that passes in through the closed end of the case A, as shown in Fig. 1, so that by adjusting the said screw the valve C may be held to its seat with more or less force, as may be required. In the valve C, upon the opposite sides of the stem D, are formed two passages or ports, $c^1\ c^2$, in such positions that when the said valve is in the position shown in Figs. 1 and 2 the passages $c^1\ c^2$ may be opposite the passages $b^3\ b^1$ of the bottom B, and when the valve C may be turned one-quarter around, the said passages $c^1\ c^2$ may come opposite the passages $b^2\ b^4$, also formed in the bottom B.

In using the device, it is connected with the

boiler at a little higher level than the water-line. The passage b^1 is connected by a pipe with the top or steam-space of the boiler. The passage b^3 is connected with the boiler at the water-line. The passage b^2 is connected with the water-cistern, which must be at a higher level than the device. The passage b^4 is connected with the cistern to convey away the steam or air from the chamber A. To the valve C, in the passage c^2 , is secured the lower end of a pipe, G, the upper end of which projects nearly to the closed upper end of the vessel A, so that water may pass into and steam or air out of, and also that water may pass out of and steam into, the said chamber without the two streams interfering with each other. The movement of the valve C is limited by a stop-pin, H, attached to the edge of said valve, and which strikes alternately against the stop-pin I, attached to the bottom B. By this construction, as the valve C is turned so as to make the passages $c^1\ c^2$ correspond, respectively, with the passages $b^2\ b^4$, the water will flow, by its own weight, into the chamber A, while the air or steam in said chamber escapes into the said cistern, or some other receiver. When the valve C is so adjusted as to make the passages $c^1\ c^2$ correspond, respectively, with the passages $b^3\ b^1$, the water will flow, by its own weight, into the boiler, while an equal amount of steam escapes into the chamber A. The valve-crank E may be operated by hand, or by a cam or other mechanical device driven by the machinery.

Having thus described my invention, I claim as new and desire to secure by Letters Patent—

The case A, bottom B, provided with the four passages $b^1\ b^2\ b^3\ b^4$ and the stops I, the valve C, provided with the two passages $c^1\ c^2$ and the stop H, and the pipe G, constructed and arranged to operate, in connection with each other, a steam-boiler, and a supply-cistern, substantially as herein shown and described.

CHARLES WRIGHT.
